DESIGN FOR A WHEELED TOY

George M. Wallner, Iron Mountain, Mich., assignor to Dudley W. Moor, Jr., and Eugene M. Belknap, Toledo, Ohio

Application April 26, 1945, Serial No. 119,232

Term of patent 14 years

(Cl. D34—15)

To all whom it may concern:

Be it known that I, George M. Wallner, a citizen of the United States and resident of Iron Mountain, in the county of Dickinson and State of Michigan, have invented a new, original, and ornamental Design for a Wheeled Toy, of which the following is a specification, reference being had to the accompanying drawing, forming a part thereof.

In the drawing, Fig. 1 is a top perspective view of a wheeled toy showing my new design, and Figs. 2 and 3 are top plan and end views, respectively, thereof.

I claim:

The ornamental design for a wheeled toy, substantially as shown.

GEORGE M. WALLNER.
